(57) **CLAIM**

The ornamental design for a recycling container, as shown and described.

DESCRIPTION

FIG. 1 is a perspective view of a first embodiment of a recycling container;

FIG. 2 is a front view of the recycling container of FIG. 1; FIG. 3 is a rear view of the recycling container of FIG. 1; FIG. 4 is a side view of the recycling container of FIG. 1; FIG. 5 is a side view of the recycling container of FIG. 1; FIG. 6 is a top view of the recycling container of FIG. 1; FIG. 7 is a bottom view of the recycling container of FIG. 1;

FIG. 8 is a perspective view of a second embodiment of a recycling container;

FIG. 9 is a front view of the recycling container of FIG. 8; FIG. 10 is a rear view of the recycling container of FIG. 8; FIG. 11 is a side view of the recycling container of FIG. 8; FIG. 12 is a side view of the recycling container of FIG. 8; FIG. 13 is a top view of the recycling container of FIG. 8; FIG. 14 is a bottom view of the recycling container of FIG. 8;

FIG. 15 is a perspective view of a third embodiment of a recycling container;

FIG. 16 is a front view of the recycling container of FIG. 15; FIG. 17 is a rear view of the recycling container of FIG. 15; FIG. 18 is a side view of the recycling container of FIG. 15; FIG. 19 is a side view of the recycling container of FIG. 15; FIG. 20 is a top view of the recycling container of FIG. 15; FIG. 21 is a bottom view of the recycling container of FIG. 15;

The broken lines in the drawings depict portions of the recycling container that form no part of the claimed design.
